UNITED STATES PATENT OFFICE

AXEL FOLKE CARLSON, OF CAMBRIDGE, MASSACHUSETTS, ASSIGNOR TO REECE SHOE MACHINERY COMPANY, OF BOSTON, MASSACHUSETTS, A CORPORATION OF MAINE

SEWING MACHINE

Application filed September 27, 1929. Serial No. 395,667.

This invention relates to welt sewing machines, and as herein illustrated, is adapted more especially to a welt sewing machine, for example a machine of the class known as welt-and-turn machine for the stitching of shoes. An example of this class of machine is the Reece welter wherein the shoe upper is stitched to the lip of the insole and to the welt strip, exemplified by the patents of 5 Zaleski et al. No. 1,288,366 of December 17, 1918, and No. 1,361,952 of December 14, 1920, and characterized by the use of a crank shaft as the main or stitching shaft, operating various of the stitching instruments through 10 links and levers. The novel features of the present invention however are applicable to other classes and types of welt and other sewing machines.

The general object of the present invention 20 is to provide an improved means for effecting the cutting of the thread and the holding of the thread end in readiness for the commencing of a new seam, the same being effected by a manual movement of the work or thread 25 after the termination of a seam and the pulling out of a certain amount of thread.

A particular object is to afford a convenient and effective thread cutting means or thread holding means, or the two combined, applying 30 cable to a machine provided with mechanism for severing or holding the end of a welt strip after the completion of the seam. My prior application No. 280,504, filed May 25, 1928, illustrates a Reece welting machine containing 35 mechanism for severing and holding the end of the welt, operable by a manual movement after the completion of the stitching and the stoppage of the machine, and the present invention is illustrated as an additional improvement upon or attachment to 40 the particular machine shown in said application.

Other objects and advantages of the present invention will be pointed out in the hereinafter following description of an illustrative embodiment or will be apparent to those skilled in the subject of welting machines.

To the attainment of the aforesaid objects and advantages, the present invention consists 50 in the novel welt sewing machine and the

novel features of combination, arrangement, operation, construction and detail as herein illustrated or described.

In the accompanying drawings Figure 1 is a general left elevation of a portion of a Reece 55 welt sewing machine embodying the present invention, this corresponding substantially with Figure 1 of said application 280,504, modified to incorporate the present invention.

Fig. 2 is also a left elevation but showing only the attachment containing the thread cutting and holding means of the present invention, the same on an enlarged scale and turned upright for convenience of illustration.

Fig. 3 is a front elevation of the parts shown in Fig. 2, as seen from the right side of Fig. 2.

Fig. 4 is an underneath view of the parts 70 seen in Figs. 2 and 3.

Fig. 5 is a view similar to Fig. 2, but showing separately the fixed bracket member carrying the movable parts.

Fig. 6 is a view similar to Fig. 5 showing 75 the unlatching member detached.

Fig. 7 is a similar view showing the thread cutter detached.

Fig. 8 is a similar view showing the thread holder detached.

The figures are shown with their parts in the position occupied by them after the machine has stopped, the operator has tripped the welt severing and holding mechanism, the welt gripper has come forward and gripped the welt, the welt knife has cut the welt and retracted, and the thread cutting and holding mechanism is in readiness for operation by a manual movement of the work and thread in accordance with the present 90 invention.

In one aspect the present invention may be outlined as comprising, in a sewing machine, a thread cutter or blade, and a thread holder, with means for latching the cutter and holder in their set positions, spring means for operating the cutter and holder when unlatched and a shiftable member engageable by the pulled out thread between the stitching point and the work adapted to be 100

shifted by the thread for unlatching the latch means and thereby effecting the cutting and holding of the thread end.

The position of the shoe S is indicated in Fig. 1. The shoe upper U and the insole lip L are to have attached to them the welt W in this class of machine. The type of machine may be that comprising a tall post with an upper frame portion or head 11 carrying fore-and-aft frame walls, the wall 12 corresponding with the left frame wall of the Zaleski et al. patents.

The main or stitching shaft 18 may be a crank shaft having connections (not shown) extending to the several stitching instruments. A needle 19 is shown, oscillating about an axle 20 and operated for example as in the Zaleski patents to penetrate the welt, upper and lip, receive the thread from a looper, and retract to draw the thread through the work in each stitch cycle. The feed may be effected as usual through the aid of a feed point 21 swung rearward and forward about a horizontal feed bar or slide 22 extending right and left and operated from the main shaft to reciprocate along the direction of feed by a movement equaling the length of a single stitch. A looper, take-up and other usual stitching instruments and operating connections will be understood, or ascertained from the prior patents.

The welt gripper or holding device 29 shown as comprising an under jaw 30 and an upper jaw 31 each provided with serrations for better gripping the leather. One of the jaws, preferably the upper jaw, is swingable for opening and closing the gripper, and is shown pivoted at 32 to the shank of the lower jaw.

The lower gripper jaw 30 is formed at the forward end of a sliding shank 37, the rear end of which slides through a guiding block 38 which is swivelled upon the portion 15^a of the bracket 15, thus permitting the gripper as a whole to be swung right and left for purposes to be described. Near its rear end the shank carries a stop pin 40 striking against the block 38 and limiting the forward movement of the gripper. The shank at its left side carries a stud 41 pressed upon by a spring 42 tending always to throw the shank and gripper device rearwardly to the normal or retracted position.

The further details of the welt gripper are not necessary to be described, as said application can be referred to for a full description thereof, and this applies also to the welt severing blade and its details of mounting and actuation. The several motions of the gripper and the blade are effected from a single oscillating actuator which is put through its rocking movements at the proper time and is mounted on the bracket 15 beneath the shank of the gripper. The actuator is on a rock shaft 78 extending trans-

versely, and at its left end, or the rear end of Fig. 1, is provided with a crank 79 whereby the shaft may be rocked in a forward direction or clockwise through an arc of about 90° more or less.

The arm or rocker 81 on the shaft 78 carries an arc flange 82 which thrusts the gripper forwardly. The shaft also carries a separate rocker arm 85 for actuating the knife and closing the gripper. Other portions 75 need not be described.

The forward and return rocking motion of the actuator parts are shown effected from a power driven shaft 95 under control of the hand. The shaft carries a worm 96 engaging worm wheel 97 on one of the shafts 18 of the machine. A second worm 98 on the shaft 95 engages a worm wheel 99 which constitutes the driving member of a clutch, the driven member 100 of which is in the form of a disk 85 or wheel inside the wheel 99 and revolving on a shaft or axle turning in a circular bracket projecting leftward from a bracket 14 secured at the left side of the frame wall 12. The operation is such that the wheel or driving clutch member 99 turns constantly in counterclockwise direction in Fig. 1 and at a speed for example of 150 R. P. M. more or less, thus making a single rotation in something under one half second. The clutch 95 driven member carries a crank or pin 101 and, as will be explained, is arranged to make a single rotation at each actuation and to come to rest with the crank 101 in the normal or lower position as shown in Fig. 1. A connecting rod 102 extends from the clutch crank 101 to the crank 79 on the rock shaft 78, the complete rotation of the clutch crank thus oscillating the rocker crank upwardly and downwardly to give the rocking parts the 90° 105 more or less rocking motion referred to. The connecting rod 102 is coupled by universal joints at its upper and lower ends to its respective cranks on account of the differences in planes of action.

The clutch may be of a well known type making a single rotation and stop and need not be described in detail. The driving member has its web formed with a number of apertures 104, each of which may be engaged so as to quicken the closing of the clutch. A stop dog 105 is carried on the driven clutch member being pivoted thereon by a pin 106 which also constitutes a clutch pin adapted to engage in one of the apertures 104. A flat spring 107 presses the dog and pin to the right, tending to engage the clutch. The dog has a tilting movement which prevents its reengaging the stopping part until a full turn has taken place.

Cooperating with the dog 105 is a clutch latch or hook 109 in the form of a lever pivoted upon a bracket portion 14^b. A finger 110 secured to the shaft of the latch lever 109 is connected by a spring 111 with the bracket, 130

thus tending to throw the latch 109 in position to engage and stop the clutch driven member. The latch has a downwardly extending tail 113, the lower end of which has an offset thin contact flange 114.

5 In order to throw the latch and permit the clutch to close for one revolution at will the following manually controlled device may be employed. A contact 116 having an inclined 10 undersurface is formed at the left end of a square shank 117 pivoted to a bent arm 119 and pulled upon by a spring 120 tending to hold the contact in the normal position shown in Fig. 1. The bent arm is mounted on a fulcrum shaft or axle 121 having its bearings in 15 extensions 17 at the left side of the frame wall 12. There also projects from the axle an operating lever or controller 122 which extends downwardly and to the left in easy access to the operator. By this arrangement, 20 if the clutch control lever 122 is thrown up by the hand of the operator, or by a portion of the work or shoe held in his hand, this operates to elevate the contact 116 which engages 25 against the inclined contact 114 on the tail of latch lever 109, thus lifting the latch lever.

The actuating contact 116 on its downward return movement can yield and pass behind 30 the contact 114 and thus avoid conflict. The lifting of the latch lever 109 frees the dog 105. The spring 107 throws the clutch pin 106 to the right and it engages in one of the apertures 104, whereupon the driving clutch 35 99 rotates the driven clutch member 100. At the end of a single rotation, preferably within in a fraction of a second the dog 105 strikes the latch lever 109, which firstly cams the dog and clutch pin to the left, thus releasing the clutch and thereupon effects a positive 40 stoppage of the driven clutch member. During this rotation the connecting rod 102 causes the rocking actuator 78—85 to swing forwardly from the normal position shown in Fig. 1 and then swing back again to 45 normal.

Coming now to the mechanism more particularly constituting the present invention, this is shown mounted upon a bracket 170 attached 50 to the left side of the frame wall 12 and extending downwardly at a rear slant to bring the cutter, the holder and the latch adjacent to but slightly to the left of the stitching point, as will be clearly seen in Fig. 3. The bracket 170, as shown separately in Fig. 5, is formed with a kerf 171 to receive the pivoted thread holder. The lower 55 part of the bracket is formed with a sharpened edge 172 constituting a blade cooperating with the cutter to be described. Formed near the lower end of the bracket and extending through the kerf part thereof is shown a pivot hole 173 receiving the pivot for the cutter and holder. Further up is shown a 60 stud hole 174 for a guide stud to be described, also in dotted lines a stud hole 175 formed in the rear part of the bracket.

The cutter 176 is seen in Figs. 2 and 3 and separately in Fig. 7. This is a rocking member formed with a hub 177 turning on a pivot 70 stud to be described engaging the hole 173. The cutting edge 178 of the cutter cooperates with the edge 172 of the bracket. The cutter is extended above its pivot and the extension is formed with a hole 179 to receive the stud 75 of a spring. A further extension 180 constitutes a tail by which the cutter is latched in the open position shown in Fig. 2. At the lower part of the cutter adjacent its cutting edge is shown a hole 181 receiving a pin 182 80 which extends to the right so as to be able to contact and operate the thread holder to be described.

The cutter and holder are preferably operated by the snap action of a spring and for 85 this purpose a pin 183 is shown engaged in the hole 179, with a coil spring 184 extending from the pin to a pin 185 extending leftwardly from an extension bracket 186 attached at the right side of the bracket 170 90 with a holding screw 187 engaging the stud hole 175 at the right side of the bracket. The cutter swings about a pivot 188 which as seen in Fig. 3 has an enlarged head overlying the cutter, a shank of substantial diameter 95 engaging the aperture in the cutter hub 177, a threaded stud portion engaging in the left part of the main bracket, and therebeyond an unthreaded portion extending through the kerf and forming a pivot for the thread 100 holder.

The thread holder 189 is shown as a small swinging plate fitted within the kerf 171 of the bracket, its rounded lower edge 190 co-operating with the lower bevelled edges of 105 the kerf as seen in Fig. 4, where the thread T is lightly pinched between the holder and the bracket and has been cut by the cutter. The holder also has a stud hole 191 by which it is engaged upon the pivot stud 188 which 110 constitutes also the pivot for the cutter. The holder is extended above as a tail 192 forming a stop contacting the bottom of the kerf as shown in Fig. 2.

The thread holder 189 is so arranged as to 115 be engaged and thrust by the pin 182 on the cutter, so that when the cutter is actuated by its spring 184 the same actuation thrusts the holder into holding position. When the parts are restored to the latched or set position as 120 seen in Fig. 2, with the spring 184 under tension, the holder may be withdrawn to its normal or open position by means of a spring 193.

The described parts are normally set or 125 held in latched position by means of a latch bar 194 shown in Figs. 1, 2 and 3. This latch has a slot 195 engaging over a stud on the unlatching member to be described, and the latch has a downwardly extending tooth or shoulder 196 which normally engages and 130

holds the latch extension or tail 180 of the cutter against the tension of the spring 184. The parts are thus held in set position until released.

- 5 Upon release it will be understood that the spring 184 pulls the cutter tail 180 forwardly, that is, to the right in Fig. 2. After actuation the parts may be reset by thrusting the latch bar to the right until its tooth 196 engages again over the cutter tail 180 thence returning to normal position. For this purpose there is shown in Fig. 1 a mechanical connection for reciprocating the latch bar 194 to reset the parts. This connection may take the 10 form of a lever having an upstanding arm 197 and a rearwardly extending arm 198, the two forming in substance a bell crank turning on a pivot shaft 199. The rear end of the arm 198 is formed with a slot 200 engaging over 15 a stud 201 formed at a midway point on the upwardly and downwardly reciprocating connecting rod 102, so that a complete up and down movement of the rod will cause the rocking of the bell crank and thereby the forward and return movements of the latch bar for resetting the cutting and holding mechanism.

The preferred embodiment of this invention includes a shiftable unlatching member 20 which is operable by the movement of the shoe in the hand of the operator before the thread has been cut. This is preferably a movement effected after the operation of the welt severing and gripping mechanism and in 30 such a manner that the thread, between the stitching point and the work, may be caused to bear against the unlatching member which is thereby movable in a manner to effect the releasing of the cutting and holding means, 35 so that the actuating spring will operate them to cause the cutting and holding of the thread.

This feature is shown embodied herein by an unlatching bar 202 shown in left elevation in Fig. 1 and in a similar view, but broken 40 away in Fig. 2, in front view in Fig. 3 and detached in Fig. 6. This is a shiftable bar and may be movable for example in an upward direction to effect the unlatching operations. It is shown as having a notch 203 at 45 its lower end to facilitate the engaging and pressing of the thread against the bar to lift it. It is formed with two offsets as seen in Fig. 3 to accommodate the cutter and its mountings. It is also apertured or slotted at 50 204 and 205 to receive certain studs. It has a forward extension 206 to receive the end of a light spring 207 connected to a stud 208 for assisting gravity to pull down on the bar.

The guide slot 204 is shown as engaging a 55 guide stud 209 having its shank pass through the slot and thence threaded into the outer end of the stud 188. The guide slot 205 engages a stud 210 fixed in the bracket 170.

Near the center of the unlatching bar 202 60 is a threaded hole 211 carrying a stud 212, the

inner end of which carries a roller 213 engaging in the slot 195 of the latch bar 194. By this arrangement the latch bar may reciprocate forward and rearwardly for resetting purposes while the unlatching bar may be 70 lifted and thereby raise the latch bar to disengage the tooth 196 from the tail 180 of the cutter to permit the cutting and holding operations.

The operation has been generally indicated, 75 but may be further explained as follows: After the stitching of a shoe and the let up of the main pedal the machine comes to rest with the needle retracted as seen in Fig. 1 and the welt and thread free to be pulled out. The 80 operator may move the work leftward to a short extent, as indicated in said application, to draw out a limited length of welt, and thereupon strike the control lever 122, for example with the shoe, thereby tripping the clutch 99-100 and bringing about a single rotation of the crank 101, which lifts and lowers the connecting rod 102 thereby actuating the mechanism which severs and grips the welt, leaving the welt end held firmly for 85 the next stitching operation as shown in Fig. 1.

The shoe is now free to be pulled out further in order to draw more thread from the supply. The further operation is best 90 explainable on Fig. 3 where the path of the barbed needle is indicated at 19 and the position of the looper at 23. The thread T is seen extending through the looper and thence out leftward to the position of the work held in 95 the hands of the operator. It is only necessary for the operator to lift the shoe so as to bring the thread within the notch 203 of the unlatcher or bar 202, as indicated by the thread line T, and thereupon pull 100 upwardly upon the work and thread until the latter swings into the position indicated at T'. This lifts the unlatcher bar and thereby disengages the tooth 196 from the latch tail 180 of the cutter. The spring 184 thereupon 105 operates the cutter and through the cutter operates the holder. These parts therefore are snapped into cutting and holding position as shown in Fig. 4, in which position the path of the thread will remain at T' in Fig. 3. 110 The holding of the thread is not a positive gripping but is a firm frictional holding that will enable the thread to be pulled out after one or two stitches have been formed in the starting of a new seam. It will be noticed 115 from Fig. 2 that the cutter blade opens slightly wider than the holder so that a receiving recess for the thread is left between the fixed part of the bracket and the open holder. The notch 203 for receiving the thread at the foot 120 of the release member 202 is in a direct line with the thread receiving recess or jaw of the open holder and cutter, so that when the operator swings the thread up into the position T in Fig. 3, engaging the notch 203, the thread 125

130

necessarily enters the jaw or recess of the cutter and holder.

The bar 194 with the tooth 196 for latching the cutter and with the slot 195 receiving the stud 212 for unlatching purposes, may be described as a toothed member which is movable in one pair of directions, downwardly and upwardly in Fig. 2, for latching and unlatching the cutter, and movable in another pair of directions, to the right and left in Fig. 2, for reengaging and restoring the cutter in latched position.

There has thus been described a welt sewing machine embodying the features and attaining the advantages of the present invention. Since many matters of combination, arrangement, operation, structure and detail may be variously modified without departing from the principles, it is not intended to limit the invention to such matters except so far as set forth in the appended claims.

What is claimed is:

1. In a sewing machine a thread cutter and a thread holder, means for latching them in set position, spring means for operating them when unlatched, and a shiftable member engageable by the pulled-out thread between the stitching point and work adapted to be shifted by the pressure of the thread for unlatching the latch means to effect the cutting and holding of the thread.

2. In a sewing machine a thread cutter and a thread holder, means for latching them in set position, spring means for operating them when unlatched, and an unlatching member adapted to be shifted at will for unlatching the latch means to effect the cutting and holding of the thread.

3. In a sewing machine a thread cutter, means for latching the cutter in set position, spring means for operating it when unlatched, and a shiftable unlatching member engageable by the pulled-out thread between the stitching point and work, the cutter being in line between the stitching point and unlatching member, whereby the thread may be engaged in the cutter and pressed against the unlatching member to cause the actuation of the cutter.

4. In a sewing machine a thread cutter comprising fixed and movable blades, and a thread holder comprising fixed and movable parts, means for latching the cutter and holder in open position, spring means for closing them when unlatched, and a release means engageable by the pulled-out thread between the stitching point and work adapted to be shifted by the pressure of the thread for unlatching the latch means to effect the cutting and holding of the thread between the release means and stitching point.

5. In a sewing machine a thread cutter comprising a movable blade, means for latching the blade in open position, spring means for operating it when unlatched, and a shift-

able release member engageable by the pulled-out thread between the stitching point and work adapted to be shifted by the pressure of the thread for unlatching the latch means thereby to effect the cutting of the threads between the stitching point and release member. 70

6. The combination as in claim 5 and wherein the release member has a notch to receive the thread, so positioned that when the thread is engaged in the notch it also engages in the cutter. 75

7. The combination as in claim 5 and wherein is an automatic means operable from another part of the machine for opening and latching the cutter. 80

8. The combination as in claim 5 and wherein is a power operated connection for re-opening and latching the cutter. 85

9. In a sewing machine a spring-actuated thread cutter, a toothed member movable in one pair of directions to latch and unlatch the cutter and movable in another pair of directions to reengage and restore the cutter in latched position, means engageable by the pulled-out thread between the stitching point and work adapted to be shifted by the pressure of the thread for moving the toothed member to unlatch the cutter, and means for moving the toothed member to reengage and restore the cutter in latched position. 90

10. In a power driven welt sewing machine, welt severing and gripping mechanism operating beyond the stitching point and having means for operating it at will after the stoppage of the machine, a thread cutter and a thread holder, means for latching them in set position, spring means for operating them when unlatched, a shiftable member operable at will for shifting the latch means to effect the cutting and holding of the thread, and a connection from the operating means of the welt severing and gripping mechanism for resetting the thread cutter and holder in latched position. 100

11. In a power driven welt sewing machine, welt severing mechanism operating beyond the stitching point and having means for operating it after the stoppage of the machine, a thread cutter, means for latching it in set position, spring means for operating it when unlatched, a shiftable member operable at will for shifting the latch means to cause the cutting of the thread, and a connection from the welt severing mechanism operable by the welt severing action thereof for resetting the thread cutter in latched position. 110

In testimony whereof, this specification has been duly signed by:

AXEL FOLKE CARLSON. 125
